UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed March 2, 1922. Serial No. 540,459.

To all whom it may concern:

Be it known that I, MALCOLM L. COSSITT, a citizen of the United States, residing at Alameda, in the county of Alameda and 5 State of California, have invented certain new and useful Improvements in Manifolding Attachments for Typewriters, of which the following is a specification.

My invention relates to manifolding attachments for typewriters and other typing 10 machines, comprising, essentially, a manifolding ribbon; movable members carrying the ribbon and adapted to place it in and remove it from functional position in the 15 line of type impact; and a suitable frame carrying said members and adapted for ready connection with the platen-carriage of the machine.

One object of my present invention is 20 to provide a simple and effective means for releasably holding the ribbon carrying members against inadvertent or accidental displacement, thereby insuring the position of the ribbon both in and out of use. Another 25 object is to provide simple and effective means for adjusting the ribbon with respect to its width, when in functional position, in order to present it for use over practically its whole area.

Another object is to provide a manifolding attachment adapted for simple and ready connection with the platen-carriage 30 of the machine.

To these ends my invention consists in 35 the novel manifolding attachment for typewriters which I shall now fully describe, reference being had to the accompanying drawings, in which—

Fig. 1 is a perspective view of my manifolding attachment, showing it connected 40 with a bar, which is, as will be later shown, a bar at the back of the platen-carriage of the typewriter.

Fig. 2 is a perspective view of the right 45 hand or operative end of the attachment, looking at it from the side opposite to that of the view point of Fig. 1.

Fig. 3 is a cross section through the concentric turnable arm carrying members, on 50 the line 3—3 of Fig. 3.

Fig. 3^a is a longitudinal section, partly in elevation of the same on the line 3^a—3^a of Fig. 3.

Fig. 4 is an end view, enlarged, broken and partly in section on the line 4—4 of 55 Fig. 6, showing the attachment connected with the platen-carriage of a typewriter, and showing the manifolding members thrown down to functional position, the dotted lines showing them thrown up when 60 not in use.

Fig. 5 is a plan view of the operative end of the attachment.

Fig. 6 is a front view of the platen-carriage, on the line 6—6 of Fig. 7, showing 65 one of the manifolding ribbons brought down for use and another still elevated out of the way.

Fig. 7 is a top plan view showing both manifolding ribbons in functional position. 70

For the sake of simplicity, I shall first describe the attachment complete and then point out its connection with a typewriter.

Referring first to Figs. 1, 2, 3 and 3^a, 1—1 are brackets, each having an angularly directed foot 1'. In the upper ends of the brackets is rotatably mounted a rod 2, which, for the sake of constructive practice is a tubular rod as shown. This rod is adapted to be turned on its axis by means 75 of the knob 3 on one end. Fast on the rod 2, are two arms 4, one near each end. Between the arms 4 is carried a manifolding ribbon 5, which is omitted from Fig. 1, but is shown in Figs. 6 and 7. Rotatably 80 fitted upon the rod 2 is a sleeve 6, to which at each end is made fast an arm 7. Between the pair of arms 7 is carried another manifolding ribbon 8, shown in Figs. 6 and 7. The ribbon-carrying arms 4 and 7 at 85 90 each end preferably overlie each other, the arms 4 being uppermost. A thumb-piece 7' is secured to that one of the arms 7, which is nearest the knob 3 of the rod 2, the thumb-piece and the knob being in such relative position, as seen in Fig. 1, that the respective pairs of arms may be moved up or down either separately or together, by the right hand of the operator.

Freely mounted upon the rod 2, just inside the knob 3 is a lever 9, the other end of which is fitted or yoked upon a cam 10, which, as will be presently described is to be secured upon the platen-shaft of the machine. The lever 9 is provided or formed 105 with an angularly directed bar 11, which

traverses the plane of movement of the ribbon carrying arms 4 and 7. The free end of this bar 11 carries or is formed with a controlling plate 12, which is formed with a lower resilient tongue 13, and upper resilient tongue 14 and a back stop 15.

The bar 11 serves as a stop for the arms 4 and 7 at the lower limit of their movement, while the stop 15 serves to limit their upward movement. The resilient tongues 13 and 14 bear against the edge of the arms 4 and 7, and serve to frictionally hold them against inadvertent displacement in their lower and upper positions respectively.

15 The parts thus described comprise the complete attachment.

Its connection with the typewriter may now be described. 16 indicates part of a frame of a typewriter, having a platen-carriage 17 provided with a back-bar 18. Figs. 4 and 7. 19 is the platen, having a shaft 20 with a knob 21 to turn the platen.

To the back-bar 18 of the platen carriage are secured by the screws 22 the feet 1' of 25 the brackets 1, said brackets thus rising at each end and back of the platen-carriage, the rod 2 and sleeve 6 extending back of and parallel with the platen as seen in Figs. 4 and 7.

30 In connecting the attachment with the machine, the platen-shaft knob 21 is temporarily removed, and upon the exposed end of the platen-shaft, is slipped the cam 10 which enters the yoked end of the lever 9. The cam is made fast to the platen-shaft by a screw 23, and then the knob 21 is replaced on said shaft. This completes the mounting of the attachment.

In the out of use position of the manifolding ribbons, they are elevated above the platen, and in this position, they are frictionally held by the pressure of the upper spring tongue 14 against the carrying arms 4 and 7, said arms being prevented from 45 falling back any farther, by the back stop 15 of the controlling plate 12. When one of the manifolding ribbons is to be used, the operator, taking hold of the rod-knob 3 between his thumb and second finger and 50 holding said knob against rotation, presses upon the thumb piece 7' and moves the sleeve-connected arms 7 down, as shown in Figs. 1 and 6, thereby carrying the ribbon 8 down in front of the platen to lie between 55 the paper sheets, and back of the index pointer 24, and main ribbon 25—Figs. 6 and 7.

In this position, it becomes functionally operative and is there stopped by the arm 7 resting on the bar 11 of the lever 9 and is frictionally held against unintentional displacement by the lower spring tongue 13 of the controlling plate 12.

If the second manifolding ribbon 5, in 65 addition to the first one, is required, the

knob 3 is turned to rotate the rod 2 and thereby carry the arms 4 down, as seen in Figs. 4 and 7.

If desired both ribbons may be lowered and raised together.

70 In manifolding attachments wherein a relatively narrow ribbon is used, it is of advantage to provide for a shifting of the ribbon in the direction of its width, when said ribbon is in its functional position, in 75 order that substantially the whole width of the ribbon may be utilized, and its life, thereby prolonged. I have, therefore, provided for such a shift at each line spacing of the platen. This is effected by the cam 80 10 and the lever 9. When the platen is turned for line spacing the cam will successively lift and lower the lever 9 and this movement of the lever, through its connected controlling plate 12, will successively lift 85 and lower the ribbon-carrying arms, and thereby shift the ribbons slightly up and down, and thus bring them throughout their width into the line of type impact.

90 I claim:—

1. A manifolding attachment for typewriters comprising a connected pair of arms movably mounted on the platen carriage of the machine; a manifolding ribbon carried by and between said arms and adapted by 95 their movement to be carried into and out of functional position in the line of type impact; and a member lying parallel with the plane of movement of one of said arms and adapted to bear with resilient pressure 100 against the edge of said arm to yieldingly hold it in desired position.

2. A manifolding attachment for typewriters comprising a connected pair of arms movably mounted on the platen carriage of 105 the machine; a manifolding ribbon carried by and between said arms and adapted by their movement to be carried into and out of functional position in the line of type impact; and a plate lying parallel with the 110 plane of movement of one of said arms and having a resilient tongue adapted to bear against the edge of said arm to yieldingly hold it in desired position.

3. A manifolding attachment for typewriters comprising a connected pair of arms movably mounted on the platen carriage of the machine; a manifolding ribbon carried by and between said arms and adapted by 115 their movement to be carried into and out of functional position in the line of type impact; and a plate lying parallel with the plane of movement of one of said arms and having a pair of resilient tongues adapted to bear against the edge of said arm 120 to yieldingly hold it at the limits of its movement.

4. A manifolding attachment for typewriters comprising a connected pair of arms movably mounted on the platen carriage of 130

the machine; a manifolding ribbon carried by and between said arms and adapted by their movement to be carried into and out of functional position in the line of type impact; a member adapted to bear with resilient pressure against one of said arms to yieldingly hold it when its ribbon is in functional position; and means for moving said member to adjust the arms and vary the 10 position of the ribbon with respect to its width, when in said position.

5. A manifolding attachment for typewriters comprising a connected pair of arms movably mounted on the platen carriage of the machine; a manifolding ribbon carried by and between said arms and adapted by their movement to be carried into and out of functional position in the line of type impact; a member adapted to bear with resilient pressure against one of said arms to yieldingly hold it when its ribbon is in functional position; and means dependent upon the line spacing of the machine platen for moving said member to adjust the arms 20 and vary the position of the ribbon with respect to its width when in said functional position.

6. A manifolding attachment for typewriters comprising a connected pair of arms movably mounted on the platen carriage of the machine; a manifolding ribbon carried by and between said arms and adapted by their movement to be carried into and out of functional position in the line of type impact; a member adapted to bear with resilient pressure against one of said arms to yieldingly hold it when its ribbon is in functional position; and means dependent upon the line spacing of the machine platen for moving said member to adjust the arms and vary the position of the ribbon with respect to its width when in said functional position, said means comprising a cam on the platen shaft and a 40 lever actuated by said cam and connected with said member.

7. A manifolding attachment for typewriters comprising a pair of brackets mounted upon the platen carriage of the machine; a rod rotatably mounted in said brackets and provided with a knob on its end to turn it; a pair of arms carried by said rod; a manifolding ribbon carried by and between said arms and adapted by their movement to be carried into and out of functional position in the line of type impact; a sleeve mounted for independent rotation upon said rod; a pair of arms carried by said sleeve, one of said arms having a finger piece in the vicinity of the rod knob, for moving said arm; and a manifolding ribbon carried by the sleeve arms adapted to be carried by their movement into and out of functional position.

65 8. A manifolding attachment for type-

writers comprising a pair of brackets mounted upon the platen carriage of the machine; a rod rotatably mounted in said brackets and provided with a knob on its end to turn it; a pair of arms carried by said rod; a manifolding ribbon carried by and between said arms and adapted by their movement to be carried into and out of functional position in the line of type impact; a sleeve mounted for independent rotation upon said rod; a pair of arms carried by said sleeve, one of said arms having a finger piece in the vicinity of the rod knob, for moving said arm; a manifolding ribbon carried by the sleeve arms adapted to be carried by their movement into and out of functional position; and a controlling plate provided with resilient tongues bearing against the arms at one end of the device for yieldingly holding them at the limits of their movement.

9. A manifolding attachment for typewriters comprising a pair of brackets mounted upon the platen carriage of the machine; a rod rotatably mounted in said brackets and provided with a knob on its end to turn it; a pair of arms carried by said rod; a manifolding ribbon carried by and between said arms and adapted by their movement to be carried into and out of functional position in the line of type impact; a sleeve mounted for independent rotation upon said rod; a pair of arms carried by said sleeve, one of said arms having a finger piece in the vicinity of the rod knob, for moving said arm; a manifolding ribbon carried by the sleeve arms adapted to be carried by their movement into and out of functional position; a controlling plate provided with resilient tongues bearing against the arms at one end of the device for yieldingly holding them at the limits of their movement; and means for moving said plate at each line spacing of the platen for adjusting the functional positions of the ribbons with respect to their width.

10. A manifolding attachment for typewriters comprising a pair of brackets mounted upon the platen carriage of the machine; a rod rotatably mounted in said brackets and provided with a knob on its end to turn it; a pair of arms carried by said rod; a manifolding ribbon carried by and between said arms and adapted by their movement to be carried into and out of functional position in the line of type impact; a sleeve mounted for independent rotation upon said rod; a pair of arms carried by said sleeve, one of said arms having a finger piece in the vicinity of the rod knob, for moving said arm; a manifolding ribbon carried by the sleeve arms adapted to be carried by their movement into and out of functional position; a controlling plate provided with resilient tongues bearing against

- the arms at one end of the device for yieldingly holding them at the limits of their movement; and means for moving said plate at each line spacing of the platen for adjusting the functional positions of the ribbons with respect to their width, comprising a cam on the platen shaft and a lever actuated by the cam and connected with the controlling plate.
- 10 11. In combination with a typewriter platen and the carriage therefor having a longitudinally directed bar lying back of the platen and below the level thereof; a

pair of uprising brackets each having an angularly directed foot secured to the rear face of said bar, one at each end thereof; a member rotatably mounted in said brackets; a pair of spaced arms secured to said member; and a manifolding ribbon carried by and between said arms and adapted by their movement to be carried into and out of functional position in the line of type impact.

In testimony whereof I have signed my name to this specification.

MALCOLM L. COSSITT.
